UNITED STATES PATENT OFFICE.

CLYDE TOWNSEND, OF NEWPORT NEWS, VIRGINIA.

AUTO SIGNAL-ARM.

1,342,007.

Specification of Letters Patent.

Patented June 1, 1920.

Application filed October 20, 1919. Serial No. 331,863.

To all whom it may concern:

Be it known that I, CLYDE TOWNSEND, a citizen of the United States, residing at Newport News, in the county of Warwick 5 and State of Virginia, have invented new and useful Improvements in Auto Signal-Arms, of which the following is a specification.

This invention relates to signaling devices, particularly to those of the type used upon automobiles for indicating to following traffic an intended change in the direction of travel of the vehicle, and has for its object the provision of a signal arm so 10 constructed as to be mounted upon the side of the body of an automobile with the handle portion projecting within convenient reach of the driver whereby the arm may be swung to extend laterally beyond the car 15 in clearly visible position to indicate that the driver intends to make a turn or intends to stop.

An important object is the provision of a device of this character which is so simply 20 constructed and operated that it will not interfere with the necessary maneuvers occasioned by a change in direction.

An additional object is the provision of a device of this character which will be 25 simple and inexpensive in manufacture, highly efficient in use by day or night, durable in service, and a general improvement in the art.

With the above and other objects and advantages in view, the invention consists in 30 the details of construction to be hereinafter more fully described and claimed, and illustrated in the accompanying drawing in which—

Figure 1 is a fragmentary longitudinal sectional view through an automobile, showing my device in normal position and in side elevation,

Fig. 2 is a plan view showing the device 45 swung into signaling position, and

Fig. 3 is a detail sectional view.

Referring more particularly to the drawings, the letter A designates a portion of the side of the body of an automobile. In 50 carrying out my invention I provide a device which includes an upright post or standard 10 carrying at its lower end an attaching plate portion 11 conformingly engaging upon and suitably screwed or bolted 55 to the top edge of the body A at the desired

location adjacent the driver. This post 10 carries at its upper end a reduced portion 11 which has its extremity threaded. Disposed upon this reduced portion and mounted for revoluble movement thereon is a paddle 12 60 which is bent intermediate its ends whereby the ends will be disposed in planes lying at right angles to each other. This paddle is provided with a suitable hole engaged upon the extension 11. The paddle is so 65 mounted that the horizontal portion thereof 13 constitutes the handle and the vertical portion 14 thereof constitutes the signal blade and this portion 14 may be painted any desired color to attract attention. Disposed upon the reduced extension 11 and engaging upon the top of the horizontal portion 13 of the paddle is a spring washer 15 which is engaged by a clamping nut 16, for the purpose of adjusting the tension of the 70 spring washer, and superposed upon the nut 16 is a lock nut 17.

In the operation of the device it will be seen that under normal conditions the paddle is disposed to extend longitudinally of 80 the automobile. When the driver intends to make a turn or stop, it is merely necessary that he grasp the end of the portion 13 constituting the handle, and swing the paddle so that it will extend at right angles 85 to the gear. By adjusting the nut 16 the paddle may be so adjusted as to move with the desired stiffness so that it will not move accidentally.

For night use I provide upon the portion 90 14 of the paddle, a suitable light which may be an incandescent bulb 18 connected by suitable wires with a source of current which may conveniently be one or more dry cells.

From the foregoing description and a study of the drawings it will be apparent that I have thus provided a very simple and inexpensive signaling device which will be positive in operation, which does not require elaborate manipulation, and which will efficiently perform all the functions for which it is intended.

While I have shown and described the preferred embodiment of my invention, it 105 is of course to be understood that I reserve the right to make such changes in the form, construction, and arrangement of parts as will not depart from the spirit of the invention or the scope of the subjoined claim. 110

Having thus described my invention, I claim:

A device of the character described comprising an attaching plate adapted to be secured upon the upper edge of the side of a vehicle body in conforming engagement therewith, a standard rising from said plate, a reduced extension on said standard defining a shoulder, said extension being threaded, a paddle bent intermediate its ends to provide vertical and horizontal portions, the horizontal portion being provided intermediate its ends with a hole revolvably engaged upon said extension, a spring dis-

posed upon said extension and engaging the top of said paddle, and a clamping nut threaded upon said extension and engaging said spring, said nut being adjustable whereby to regulate the tension of the spring, the vertical portion of said paddle extending outwardly of the vehicle body to serve as a signal arm and the free end of the horizontal portion extending within the body of the vehicle and being laterally bent for engagement by the hand or arm of the operator.

In testimony whereof I affix my signature.

CLYDE TOWNSEND.
